EX

OR D 5,737

UNITED STATES PATENT OFFICE.

CHARLES SELTMAN, OF WASHINGTON, DISTRICT OF COLUMBIA, ASSIGNOR
TO SOMERVILLE & LEITCH, OF SAME PLACE.

DESIGN FOR A HYDRANT.

Specification forming part of Design No. 5,737, dated April 2, 1872.

Specification describing a Design for Hydrants, invented by CHARLES SELTMAN, of Washington city, in the District of Columbia, and assigned by him to Thomas Somerville and Robert Leitch, of the same place.

The nature of the design is fully illustrated and represented in the accompanying photographic illustration, to which reference is made.

A represents the post or body of the hydrant; B, a base or pedestal for the same; C, its cap; and D, its discharge-spout. The post A is ornamented with a series of ribs, *e e e*, formed in relief, in depressions running spirally around the post, whose surface is left otherwise plain, so as to represent cords wrapped around the post and sunken into the surface thereof, as shown in the photograph. The base B is octagonal, with plain faces. A molding formed of two parts, *h* and *i*, is interposed between this plain octagonal base B and the post A. The cap C is formed of two parts, an octagonal body and a covering-plate. The faces of the body of the cap are ornamented alternately with a rounded projection or bas-

relief, *m*, and with a shell, *n*, formed partly in *intaglio*, as clearly illustrated in the photograph, and it is neatly finished on its upper and lower border with moldings *S S*. The covering-plate of the cap is ornamented with a series of leaves, *t t t*, radiating with a graceful curve from an elevated center, which is crowned with an acorn or knob, *p*. The spout D is formed to represent a dragon-head, and projects from one of the faces of the cap C in the place of one of the bas-reliefs *m*, as shown in the photograph.

What I claim as my invention is—

1. The design for the cap C of the hydrant, as shown.
2. The design for a hydrant, comprising the ornamental features of the post A, cap C, spout D, and base B, combined as shown.

Witness my hand to this specification of my design for hydrant.

CHARLES SELTMAN.

In the presence of—

DAVID A. BURR,
F. H. BURR.
